Assignment

S. S. Putnam & Co.

Letter Patent No. 2378. Dated Aug. 7. 1866.

Design for a Trade Mark.

The Schedule referred to in these Letters Patent and making part of the same,

To all whom it may concern:

Be it known that S. Silas S. Putnam of Dorchester
in the County of Norfolk and State of Massachusetts, have invented
a new Design for a Trade Mark, of which the following
is a full, clear, and exact description, reference being had to the
accompanying drawing making part of this Specification in which
is represented my new Design.

In the said drawing is represented the figure of a
Horseshoe, on the face of which are the words S. S. Putnam
& Co. Horseshoe Makers.

Within the space enclosed by the Horseshoe are
two Horseshoe Nails, one of which is placed vertically with
its point uppermost while the other is bent around, as seen in the
drawing, the two forming the letter P.

Claim.

What I claim as my invention and desire to secure by Letters
Patent, is

The Design for a Trade Mark substantially as shown and described
herein.
